UNITED STATES PATENT OFFICE

2,594,770

FEED AND RAMMER ARRANGEMENT AT
AUTOMATIC FIREARMS

Victor Hammar and Gustaf Dahlbäck, Bofors,
Sweden; Hedvig Irene Dahlbäck, administratrix
of said Gustaf Dahlbäck, deceased, assignors to
Aktiebolaget Bofors, Bofors, Sweden, a Swedish
company

Application November 5, 1945, Serial No. 626,643
In Sweden February 7, 1942

Section 1, Public Law 690, August 8, 1946
Patent expires February 7, 1962

8 Claims. (Cl. 89—33)

1

The present invention relates to a feed and rammer arrangement for automatic firearms, in which the magazine is provided above the loading bridge and from which a cartridge fed downward thereto is delivered and set up in the breech by an automatically operating rammer, and the invention is substantially characterized by two successively operating feed-down mechanisms, one of which is actuated at the recoil of the tube and is so arranged that it feeds down onto the loading bridge the undermost cartridge in the magazine, while the other feed-down mechanism is actuated at the counter-recoil of the tube and is so arranged that it feeds down one step, whereas the other cartridges remain in the magazine. This arrangement of downward feed is made possible because the loading bridge is provided with a swingable cartridge flute acting as a carrier for the ejected cartridge-case which is thus able to pass the incoming cartridge fed down to the charging bridge during the recoil. The invention enables considerable reduction of vibration of the fire-arms during shooting.

Other features of the invention will hereafter be described in greater detail with reference to the embodiment illustrated in the attached drawings; wherein:

Figs. 1a and 1b, taken together, illustrate an automatic cannon in longitudinal section wherein the parts are shown in the position where the recoilable system is returning to its rear position.

Figs. 2a and 2b, taken together, show a similar section but viewed from the opposite side and with the parts in the position where the rammer has been thrown forward and the cartridge is on its way to the breech.

Figs. 3a and 3b, taken together, illustrate, also in longitudinal section, the cannon in position of counter-recoil and viewed from the same side as in Figs. 2a and 2b.

Fig. 4 is finally a section along the line IV—IV in Fig. 1.

The tube 1 is provided with a breech block 2 of known kind which is automatically opened after shooting, whereby the empty cartridge-case is ejected, and thereafter is automatically closed as soon as the next cartridge has been delivered. The automatic loading arrangement consists partly of a rammer arrangement and partly of a feed down arrangement and is enclosed in the

2

mechanism box 3 forming a continuation of the recoil mantle 4. The loading bridge is fixed to the rear end of the tube and consequently takes part in the recoil movement of the tube. Said bridge 5 consists of a rear cartridge flute 6 provided at the front with a flute 7 journaled for up and down rotation about a pin 8. Behind the first cartridge flute 6 is another cartridge flute 9 fixed to the mechanism box 3 which consequently does not take part in the recoil movement. The rotatable cartridge flute 7 abuts at the front against the breech block and is consequently held in raised position when the breech is closed, i. e. when the breech block is in its upper position.

When the breech block is opened, the cartridge flute 7, however, is held for a predetermined time (see Fig. 1) in its raised position by means of a pawl 36 and serves therefore as a carrier for the empty cartridge-case. When ejected this cartridge-case is carried obliquely downwards below the cartridge flute 7 and is removed by the deflector 12 (see Fig. 2) fixed to the lower side of the mechanism box 3. As soon as the cartridge-case has been removed, the cartridge flute 7 is disengaged and falls down into a position parallel to the axis of the tube, thus forming a continuation of the cartridge flute 6. When the next cartridge has been delivered to the breech, the breech block is closed automatically in known manner whereby the flute 7 is once more raised by the breech-block to its initial position (Fig. 3). The rammer mechanism that throws the cartridge fed down on the cartridge flutes 6 and 9 into the breech 13 is arranged at the rear of the mechanism box 3 and consists of the rammer 14, the guide bar 15, the rammer spring 16 and the pawl arm 17. The rammer 14 consists of a carriage displaceably journaled in two guides 11 fixed to the inner walls of the mechanism box 3. A member 18 extending downwardly from the rammer carriage encloses the guide bar 15. The rammer spring 16 is arranged about the guide bar 15 and abuts at the front against the members 18 of the rammer carriage and at the rear against the rear wall of the mechanism box 3.

When the tube recoils the rammer is actuated by an extension of the loading bridge 5 and is displaced backwards while simultaneously com-

pressing the rammer spring 16. When this spring is sufficiently compressed, the pawl lever 17 snaps in behind the member 18 of the rammer 14 and the extension of the charging bridge is disengaged. The rammer is kept in locked position until the recoil movement has been completed and until counter-recoil movement begins when the pawl lever 17 is automatically disengaged. Meanwhile the breech block has been opened, the empty cartridge-case has been ejected and the swinging cartridge flute 7 has come to downward position. When the rammer is free from the pawl arm 17 it is displaced rapidly forwards by the action of the rammer spring to its initial position, thereby bringing with it the cartridge fed down to the cartridge flute of the loading bridge. Thereafter the inertia of the cartridge propels it forwards into the breech 13 of the tube. As soon as the cartridge is in place and the breech block closed, firing takes place automatically.

For the downward feed of the cartridges to the loading bridge there are two successively operating feed down mechanisms, one of which is actuated at the recoil movement of the tube and delivers to the loading bridge the undermost cartridge in the magazine. The other feed down mechanism is actuated at the counter-recoil movement of the tube and advances the remaining cartridges one step.

The feed down mechanism operating during the counter-recoil movement is placed according to the embodiment illustrated in the attached drawings on the right side of the mechanism box 3 and consists of five spring urged cartridge guides 20 swingably journaled in the feed down arm 21. This arm is vertically displaceable and its lower end is connected to a double arm lever 22 swingably journaled in the mechanism box about the shaft 23. The fore end of the lever 22 is provided with a roller 24 running in a guide groove 25 at the right side of the loading bridge 5. The guide groove 25 is so shaped that the lever 22 is given a swinging movement corresponding to the to and fro movement of the loading bridge during the recoil and counter-recoil, whereby the feed-down arm 21 connected to the lever 22 is given an upward and downward movement. The cartridge guides 20 are withdrawn during upward movement of arm 21 but are held extended during downward movement whereby they feed the cartridges in the magazine one step down. The undermost cartridge is delivered to the cartridge supports 26 and 27 (Fig. 4). This cartridge was resting before delivery against three rotatable star-shaped support wheels 28 arranged on a common, freely journaled shaft 29 and so arranged that, upon downward movement of the cartridge guides 20 said shaft 29 is displaced somewhat to the side and simultaneously rotated permitting the cartridge to fall down on the supports 26, 27. A spring loaded lever 26, 27 returns shaft 29 with the support wheels 28 to initial position.

The feed-down mechanism operating during the recoil movement is placed on the opposite side of the mechanism box and is substantially of the same construction as the right feed-down mechanism. It consists of a cartridge guide 30 (Fig. 4) connected to the feed-down arm 31 in turn connected to a double arm lever 33 journaled on a shaft in the mechanism box and provided at its fore end with a roller 34 running in a guide groove 35 on the left side of the loading bridge. During the recoil the feed-down arm 31 is displaced with the cartridge guide downwards

and then feeds down to the loading bridge the undermost cartridge positioned on the supports 26 and 27. This is made possible by the supports 26 and 27 being swingably suspended and subjected to the action of spring 26a so that they are forced to the side as the cartridge is fed downward.

For preventing the cartridges from being thrown from their positions in the magazine at high elevations or as a result of vibrations there are provided at the left inner wall of the mechanism box six cartridge holders 32 (Fig. 4). All the cartridge holders are adapted to swing aside so that the cartridges can pass down and are spring urged in spread out position.

Having now particularly described the nature of our invention and the manner of its operation, what we claim is:

1. In an automatic firearm having a recoilable tube, a feed and rammer device comprising a loading bridge, a magazine located above the bridge, an automatically operating rammer adapted to propel into the breech of the firearm a cartridge resting on the bridge, and two successively operating feed-down mechanisms adapted to feed cartridges from the magazine to the bridge, one mechanism being actuated by recoil and the other by counter-recoil of the tube, the recoil actuated mechanism comprising means engaging the lowermost cartridge in the magazine and means for moving said first means toward the bridge as the tube recoils, whereby the lowermost cartridge in the magazine is fed to the bridge when the tube recoils, and the counter-recoil actuated mechanism comprising means engaging all but the lowermost cartridge in the magazine, and means for moving the last-mentioned means toward the bridge as the tube is moved by counter-recoil, whereby all the other cartridges are fed down one step in the magazine.

2. A device as claimed in claim 1 further comprising at least one spring biased cartridge support and wherein said counter-recoil actuated mechanism is adapted to feed the undermost cartridge in said magazine onto said support.

3. A device as claimed in claim 1 wherein said recoil actuated mechanism comprises a groove in said bridge, a double arm lever guided in said groove, a feed arm actuated by said lever for vertical reciprocating movement, and a cartridge guide connected to said feed arm.

4. A device as claimed in claim 2 wherein said recoil actuated mechanism comprises a groove in said bridge, a double arm lever guided in said groove, a feed arm actuated by said lever for vertical reciprocating movement, and a cartridge guide connected to said feed arm, said feed arm and cartridge guide being displaceable downwardly during recoil to deliver to said bridge the cartridge resting on said support.

5. A device as claimed in claim 1 wherein said rammer comprises a carriage journaled for displacement in two fixed guiding supports, a guide bar, on which said carriage is slidably mounted, and a compression spring surrounding said guide bar and abutting against a fixed member of said carriage at the forward end and against a fixed support at the rear end.

6. A device as claimed in claim 5 further comprising an extension on said bridge arranged to engage and displace said rammer on recoil of the tube and to compress said spring, and a pawl arranged to engage said member when said spring is fully compressed.

7. In combination with a device as claimed in

claim 2, a breech block mechanism adapted for automatic actuation and comprising a vertically reciprocable key, said second cartridge flute in raised position abutting against said key when said mechanism is closed, and a pawl arranged to hold said flute in raised position for a short interval of time after said mechanism is opened.

8. A device as claimed in claim 1 wherein a cartridge flute is stationarily arranged below said magazine, said bridge being arranged in front of said cartridge flute and consisting of a first cartridge flute and a second cartridge flute journaled for rotation about a horizontal axis transversely of said bridge.
